UNITED STATES PATENT OFFICE.

GEORGE CLAUSING, OF PORTSMOUTH, OHIO, ASSIGNOR TO THE VULCAN LAST COMPANY, OF PORTSMOUTH, OHIO, A CORPORATION OF OHIO.

LAST.

Application filed April 15, 1925. Serial No. 23,236.

My invention relates to lasts.

It is the object of my invention to provide a hinged last construction which will resist movement from one position to another but which will positively stay in either position when once moved into the position desired.

It is a further object of my invention to provide a last which will have the suitable snap action.

Referring to the drawings:

Figure 1 is a side elevation partially in section of the last showing the arrangement of the parts within the last and showing by the dotted lines the position of the last in collapsed position; and

Figure 2 is a section on the line 2—2 of Figure 1 looking in the direction of the arrow.

Referring to the drawings in detail, 1 is the toe portion of the last, 2 the instep and 3 the heel portion. The heel portion carries a transverse pin 4 which passes through a cut away portion 5 in the heel transversely thereof at the rear end of the cut away portion 5. Carried on this pin 4 within the cut away portion 5 is a link 6. This link carries intermediate its length transversely thereof a relatively heavy transverse member preferably in the form of a cylinder designated 7. The forward end of the link 6 is carried on a transverse pin 8 which is transverse to the forward end of the cut away portion 9 in the toe portion of the last. Within this cut away portion the forward end of the link 6 operates. The link 6 is adapted to pivot on the pins 4 and 8.

On either side of the cutaway portion 9 in the toe part of the last are located open ended cup shaped cylindrical members 9^a carrying a plunger 10 therein with an enlarged rounded head 11 fitting within the cylinder 9^a with the head normally projecting beyond the edge of the cylinder. The piston or plunger 10 has an enlarged rivet head 12 which is located on the outside of the face of the cup or cylinder 9^a and thereby limits the outward movement of the head 11 of the piston or plunger. The piston or plunger is moved in that direction by the helical spring 13 which surrounds the piston rod 10, engages the bottom of the cup on the inside and the underside of the head 11.

It will be observed that when the heel part is moved with the link 6 about the pin 8 as

a pivot to the transverse cylinder 7 will engage with the head 11 and depress it against the resistance of the spring 13. Therefore the heel part will be kept either in the expanded or collapsed position and any movement from one position to the other will be resisted by the helical spring 13. This also provides a suitable snap action.

The heel is permitted to collapse by reason of the fact that its forward face is cutaway as at 14 and is normally spaced when in expanded position an appreciable distance from the rear face of the toe part which is cut away to form the face 15. The toe part extends rearwardly in a semi-circular portion 16 fitting into a semi-circular concave portion 17 of the heel part. The cylinder 7 rolls upon this surface of quadrant form which surface is designated 16. The heel part and toe part join each other on a vertical line 18 for a short distance within the bottom of the last, which line 18 intersects with the quadrant line 17 at which point a shoulder 19 is formed upon which the cylinder 7 rests.

It will be understood that I desire to comprehend within my invention such modifications as may be necessary to adapt it to varying conditions and uses.

Having thus fully described my invention, what I claim as new and desire to secure by Letters Patent, is:

1. In a last, a toe part, a heel part, a projection on the toe part of quadrant form adapted to engage with a cooperating concavity of the heel part, a right angle shoulder on either part adjacent the quadrant projection for forming a limiting shoulder, a link connecting said parts, a spring pressed plunger carried by one of said parts, and means on the link for engaging with said plunger to resist the movement of the parts from one position to the other and to hold them in either of said positions, said projection consisting of a transverse cylindrical member carried by said link, said parts having cut away portions for receiving said link and said transverse member.

2. In a last, a toe part and a heel part adapted to move on one another about a predetermined point, means on said parts for limiting the movement thereof in either direction, a transverse member carried by the link, and a plurality of spring pressed plungers carried by one of said parts adapted to engage with said member on the link to

resist the movement from one position to the other of the last parts and to hold them in position when once so moved.

3. In a last, a toe part and a heel part adapted to move on one another about a predetermined point, means on said parts for limiting the movement thereof in either direction, a transverse member carried by the link, and a plurality of spring pressed plungers carried by one of said parts adapted to engage with said member on the link to resist the movement from one position to the other of the last parts and to hold them in position when once so moved, said spring pressed plungers being mounted in tubular guide ways having means to limit the movement of the plungers in one direction and springs to impel the plungers in the other direction, the plungers having heads projecting beyond the guide ways normally.
4. In a last, a toe part and a heel part adapted to move on one another about a predetermined point, means on said parts for limiting the movement thereof in either direction, a transverse member carried by the link, a plurality of spring pressed plungers carried by one of said parts adapted to engage with said member on the link to resist the movement from one position to the other of the last parts and to hold them in posi-

tion when once so moved, said spring pressed plungers being mounted in tubular guide ways having means to limit the movement of the plungers in one direction and springs to impel the plungers in the other direction, the plungers having heads projecting beyond the guide ways normally, said plungers being located on either side of said link.

5. In a last, a toe part, a heel part, a link connecting said parts located in cut away portions therein, a partially circular projection on the toe part fitting in a concave portion of the heel part, shoulders on said parts for limiting their movement, transverse pins in each of said parts supporting said link, a relatively large transverse cylindrical member carried by said link, and a plurality of reciprocating spring pressed plungers mounted on either side of said link in the toe part in the partially cylindrical projection having heads extending beyond the face thereof adapted to be engaged by the relatively large transverse member carried by the link, whereby the movement of the parts from one position to the other is resisted and when the resistance is overcome the parts are maintained in the predetermined position desired.

In testimony whereof, I affix my signature.
GEORGE CLAUSING.
